SLIP COVER

Harold Edward Foxman, Baltimore, Md.

Application November 8, 1955, Serial No. 545,652

5 Claims. (Cl. 155—182)

This invention relates to improvements in ready-made adjustable slip covers for upholstered furniture, and particularly to the arm portions of such slip covers.

The construction of upholstered chairs and sofas has now become sufficiently standardized to provide a market for ready-made slip covers. To assure that such slip covers fit snugly and smoothly however, it is necessary that they be adjustable to the various sizes and styles of chairs differing with respect to their back rest dimensions, seat dimensions, arm dimensions, and cushion dimensions. The slip covers contemplated herein are concerned primarily with two of these variables, namely, arm widths and arm shapes.

It is among the objects of the invention to provide an adjustable slip cover for an upholstered chair having a seat, a back rest and an arm, the cover comprising a body portion including a back rest portion having a lower edge and a seat panel having a front, side and rear edges, the rear edge being connected to the lower edge of the back rest portion; an inner-and-upper arm engaging panel having a lower edge secured to a side edge of the seat panel, the inner-and-upper arm engaging panel having a curvilinear front edge adapted to outline inner and upper forward edges of the arm; and a front-and-outer arm engaging panel having an upper edge providing a curvilinear portion secured to a portion of the curvilinear front edge adapted to extend along an inner edge of the arm, and providing a substantially rectilinear portion secured to the remainder of the front edge of the inner-and-upper arm engaging panel adapted to extend along the upper front and upper outer portion of the arm.

The inner-and-upper arm engaging panel and the front-and-outer arm engaging panel are preferably provided with ends extending behind the back rest to be joined to similar extensions extending behind the other end of the back rest by suitable laces or the like. The lower edge of the front-and-outer arm engaging panel preferably has a depending pleated skirt secured thereto, permanently or detachably by suitable separable fasteners.

A more complete understanding of the invention will follow from a detailed description of the accompanying drawing wherein:

Fig. 1 is a front elevation of an upholstered chair provided with a slip cover contemplated by the present invention;

Fig. 2 is a side elevation of the chair of Fig. 1;

Fig. 3 is an elevation, partially in section, taken along line 3—3 of Fig. 1;

Fig. 4 is a fragmentary view in plan depicting a portion of the chair of Fig. 1 with the arm portions of the slip cover in extended condition;

Fig. 5 is a fragmentary front elevation of the parts in the extended condition of Fig. 4;

Fig. 6 is a section taken along line 6—6 of Fig. 5; and

Fig. 7 is a plan view of portions of a blank prior to assembly.

A typical upholstered chair as depicted in the drawing, particularly Figs. 1 and 2 thereof, comprises a back

2

rest 10 having shoulders 12, a seat 14 receiving a cushion 16, arms 18, and suitable legs, not shown. The slip cover 20 comprises a body portion including a back rest portion 22 having a lower edge 24 and lateral shoulder covering portions 26, and a seat panel 28, best shown in Fig. 4, having a front edge 30, side edges 32 and a rear edge 34. The rear edge of the seat panel is sewed to the lower edge of the back rest portion in the usual fashion. The slip cover also provides an inner-and-upper arm engaging panel 36 having a lower edge 38 secured to the side edge 32 of the seat panel, the inner-and-upper arm engaging panel also having a curvilinear front edge 40 adapted to outline the inner and upward forward edges of the arm or arms 18.

The slip cover also provides a front-and-outer arm engaging panel 42 having an upper edge 44 providing a curvilinear portion 46 secured to an adjacent portion of the curvilinear front edge 40 of the inner-and-upper arm engaging panel 36 adapted to extend along the inner edge of the arm, the upper edge of the front-and-outer arm engaging panel also providing a substantially rectilinear portion 48 secured to the remaining part of the front edge of the inner-and-upper arm engaging panel, adapted to extend along the upper front and upper outer portion of the arm or arms 18.

As clearly shown in Fig. 5 of the drawing, the seam between the inner-and-upper arm engaging panel and the front-and-outer arm engaging panel is provided with a welt 50 which continues along the rectilinear edge portion 48 to the rear of the back rest 10 as clearly shown in Fig. 2.

The inner-and-upper arm engaging panel 36 is provided with a reduced extension 52 containing a grommet 54 adapted to receive a lacing 56 as shown in Fig. 3 by which it is connected to a similar extension at the opposite end of the back rest. Tie tapes, hooks, snap fasteners, or other suitable connectors may be substituted for the laces and grommets if desired.

The front-and-outer arm engaging panel is of sufficient length to extend completely along the side of the arm 18 and the side of the back rest 10 and behind the back rest where its grommets 58 will receive suitable lacing elements 60 to join it to a similar extension from the opposite end of the back rest. It will be clear that these lacing elements 56 and 60 will be tightened sufficiently to produce a snug and smooth fit with respect to the arm and back rest portions involved. The upper edge 44 of the panel 42 may be additionally secured to the panel 36 along the upper outer edge of the arm by means of spiral pins 68 or the like, applied at suitable intervals.

The forward edge of the seat panel 28 and the lower edge of the front-and-outer arm engaging panel are shown in Fig. 5 as separably joined to a depending pleated skirt 62 having a welted edge 64, by means of snap fasteners 65 or the like.

With reference to Fig. 7, it will be noted that the inner-and-upper arm engaging panel is likewise provided with a curvilinear rear edge 66 whose curvature is selected to accommodate the greatest variety of arm conformations and sizes possible.

The great value of the slip cover thus described will be best appreciated by a brief summary of the manner in which it is installed. The back rest engaging portions 65 and the seat panel are applied from above until they engage the parts for which they are intended. They are adjusted to best advantage in accordance with known practice whereupon the portions with which the present invention is primarily concerned are adjusted. With reference to Fig. 4 of the drawing, the inner-and-upper arm engaging panel will be stretched to a position approximating that depicted in Fig. 4, whereupon it will

be folded down to engage the outer surface of its arm whereupon its extension 52 will be folded around the rear of the back rest portion of the chair at which point it will be secured to its counterpart at the opposite end of the back rest portion by means of the lacing element 56. Then it is merely necessary, referring to Fig. 5, to fold the front-and-outer arm engaging panel 42 from the extended position depicted in Fig. 5 about the forward outer edge of the arm 18 and along the outer side thereof and then folding the grommeted end about the rear portion of the back rest whereupon it too will be secured to its counterpart by means of suitable lacing elements 60 received through the grommets 58.

Thus, with great simplicity, a very pleasing aspect, as depicted in Fig. 2, will be produced, providing a snug and smooth fit for furniture having arms of widely varying styles and sizes.

It will be appreciated that when the front-and-outer arm engaging panel is folded back around the forward outer edge of the arm 18, a fold of varying size and shape will be produced, providing a third ply 68 of variable degree, depending upon the size and shape of the arm being covered, best depicted in Fig. 3.

Whereas only one form of the invention has been specifically illustrated and described, it will be recognized by those skilled in the art that the invention is widely applicable to a variety of situations. Accordingly, the invention should not be restricted to the form described beyond the scope of the appended claims.

I claim:

1. An adjustable slip cover for an upholstered chair having a seat, a back rest and an arm, said cover comprising a body portion including a back rest portion having a lower edge and a seat panel having front, side and rear edges, said rear edge being connected to the lower edge of the back rest portion; an inner-and-upper arm engaging panel having a lower edge secured to a side edge of said seat panel, said inner-and-upper arm engaging panel having a curvilinear front edge adapted to outline inner and upper forward edges of said arm and said inner-and-upper arm engaging panel having a reduced end extending behind said back rest; and a front-and-

outer arm engaging panel having an upper edge providing a curvilinear portion secured to a portion of said curvilinear front edge adapted to extend along an inner edge of said arm, and providing a substantially rectilinear portion secured to the remainder of said front edge of said inner-and-upper arm engaging panel adapted to extend along the upper front and upper outer portion of said arm.

5 2. An adjustable slip cover for an upholstered chair 10 having a seat, a back rest and an arm, said cover comprising a body portion including a back rest portion having a lower edge and a seat panel having front, side and rear edges, said rear edge being connected to the lower edge of the back rest portion; an inner-and-upper arm 15 engaging panel having a lower edge secured to a side edge of said seat panel, said inner-and-upper arm engaging panel having a curvilinear front edge adapted to outline inner and upper forward edges of said arm; and a unitary front-and-outer arm engaging panel adapted to 20 cover the front and outer surfaces of said arm, said unitary panel having an upper edge providing a curvilinear portion secured to a portion of said curvilinear front edge adapted to extend along an inner edge of said arm, and providing a substantially rectilinear portion secured to the remainder of said front edge of said inner-and-upper arm engaging panel adapted to extend along the upper front and upper outer portion of said arm.

25 3. An adjustable slip cover as set forth in claim 2 wherein said front-and-outer arm engaging panel has an end extending behind said back rest.

4. An adjustable slip cover as set forth in claim 2 wherein said front-and-outer arm engaging panel has a lower edge secured to a depending pleated skirt.

5. An adjustable slip cover as set forth in claim 35 4 wherein said skirt is detachably secured to said front-and-outer arm engaging panel.
